[57] **CLAIM**

The ornamental design for a furniture cover, as shown.

DESCRIPTION

FIG. 1 is a frontal perspective view of a furniture (chair) cover of my new design in which the inside of the seat and arms and front of the skirt are padded and quilted.

FIG. 2 is a rear perspective view of the furniture cover of FIG. 1 in which the center part of the clip cover is gathered and includes a removable ornamental bow.

FIG. 3 is a left side perspective view of my ornamental furniture cover (the opposite side being the mirror image of that shown in FIG. 3).

FIG. 4 is a full frontal view of a furniture cover with padded quilting showing my new design; and,

FIG. 5 is a full rear perspective view of FIG. 4 showing the middle section gathering and removable ornamental bow.
